MAGNETIC SWITCHING DEVICE

Herbert C. Ovshinsky, Oak Park, Mich., assignor to Tann Corporation, Detroit, Mich., a corporation of Michigan

Filed Feb. 24, 1958, Ser. No. 717,074

7 Claims. (Cl. 200—87)

This invention relates to an improved magnetic switching device, and more particularly to such a device in which a free-floating contact member is employed to positively break and make a current with a pair of electrical contact members.

In an electrical switch according to the present invention, a conductive ball confined for limited travel within a chamber is magnetically drivable into bridging engagement with a pair of spaced electrical contacts disposed within or adjacent to one end of the chamber. A pair of washerlike members confines the ball to limited movement on the end of an armature by which the ball is positively moved. The limited movement of the ball permits it to index and presents a new, randomly selected portion of its surface to the contacts each time the switch is actuated, thereby distributing wear evenly over the entire surface of the ball. In its various forms, the switch may be energized by a solenoid coil or by an externally mounted magnet, and it may be of either the normally open or normally closed type.

The principal objects of the present invention are: to provide an improved magnetically actuatable electrical switch; to provide an improved magnetically operable electrical switch having either a rapid action or a time delay characteristic; to provide an improved magnetically operable electrical switch in which a freely floating but captured ball is positively moved to and from engagement with a pair of electrical contacts; to provide an improved electrical switch of the type in which a movable conductive member changes its point of engagement with a pair of fixed electrodes when completing a circuit thereacross; to provide a movable ball on the end of a magnet so as to move therewith while being movable relative thereto so that different surface areas thereof engage the electrodes on successive actuations of the switch; to provide an improved proximity-type limit switch of either the normally open or of the normally closed type which is positively actuated by a magnet carried by a movable member of a machine or the like; and, in general, to provide an improved magnetically operable electrical switch which is of simple and rugged construction, positive in operation, and economical of manufacture.

Other objects and features of novelty of the invention will be specifically pointed out, or will become apparent when referring, for a better understanding of the invention, to the following description, taken in conjunction with the accompanying drawings, wherein:

FIGURE 1 is an elevational view of a magnetically operable electrical switch according to one embodiment of the invention;

FIG. 2 is a plan view of the switch illustrated in FIG. 1;

FIG. 3 is a sectional view of the switch illustrated in FIG. 1, taken along the line 3—3 thereof;

FIG. 4 is a broken sectional view of structure, similar to that illustrated in FIG. 3, showing another form thereof;

FIG. 5 is a broken sectional view of structure similar to that illustrated in FIG. 1, showing another form which the invention may assume;

FIG. 6 is a sectional view of the structure illustrated in FIG. 5, taken along the line 6—6 thereof;

FIG. 7 is a sectional view of structure similar to that illustrated in FIG. 1, showing still another form of the invention;

2

FIG. 8 is a sectional view of structure, similar to that illustrated in FIG. 1, showing a further form which the invention may assume;

FIG. 9 is a side elevational view of the structure illustrated in FIG. 8;

FIG. 10 is a sectional view of the structure illustrated in FIG. 8, taken along the line 9—9 thereof;

FIG. 11 is a view of structure similar to that illustrated in FIG. 8, showing another form of the invention; and

FIG. 12 is a side view of the structure illustrated in FIG. 11.

A switch 20 manufactured in accordance with an embodiment of the invention is of the relay type, being solenoid energized to close the circuit and magnetically retained in open position. The operative parts of the switch are mounted upon a base 22 which may be secured upon any convenient support 24, such as a wall or a control panel. A pair of switch contacts 26 are mounted at one end of conductive spring fingers 28, the opposite ends of which are fixed to the base 22, the opposite ends having screws or other means for securing a pair of conductors 30, of an external circuit to be controlled. The faces of the contacts 26 are positioned at an angle to each other and are centered about the upper end of the axis of a solenoid coil 32.

The solenoid coil 32 is preferably encased within a top and bottom shield 34 and 35 forming a flux path. The bottom shield 35 has a cylinder element 39 secured thereon to enclose a spring 37. Spring clips 36 are fixed to the base 22 and are shaped and positioned to engage the shield 34 and cylinder element 39 and retain the coil 32 in alignment with the contacts 26. The coil 32 is wound upon an insulating spool 38, having an upwardly extending conical portion 40 which separates the contacts 26 and provides an abutment rest therefor.

A magnetic, magnetizable or a nonmagnetizable electrically conductive ball 42 is movable within the bore 44 of the spool 38 by the solenoid plunger 46 to which it is secured by the washerlike elements 47 attached to the end of the plunger. The ball is loosely confined by the elements 47 so that it is free to change its position when it engages the inner surface of a spool 38 during the reciprocation of the plunger 46 to change the points at which the ball engages the contacts 26. The plunger 46 is held in its lower position when the coil 32 is deenergized by a magnet 48 which is mounted upon the base 22 to project outwardly beneath the plunger. The plunger 46 has a magnetizable plate 50 secured to the lower end which engages the bottom of the flux shield 35, when the plunger is raised, and which is engaged by the magnet 48 when the plunger is in lowered position. The ball 42, being free to rotate, presents a new, randomly selected area to the contacts 26 each time the plunger is moved upwardly, which assures even distribution of wear on the ball, especially with regard to the effects of contact friction and arcing.

In operation, when the coil 32 is energized, the plunger 46 is drawn upwardly, moving the ball 42 into pressure engagement with the contacts 26, springing the contacts slightly outwardly and rubbing the ball across the surfaces of the contacts with a wiping and cleaning action. When thereafter the coil 32 is deenergized, the plunger 46 moves down and positively moves the ball therewith, the movement being aided by the magnet 48 which produces a quick separation of the ball from the contacts.

The ball 42 may be made entirely of a good electrical contact material such as silver, copper and the like, or, alternatively, in the interest of greater economy it may have only a surface layer of such contact material and a hollow or solid core of less expensive material of metal, plastic or the like including a material resisting the pas-

sage of current, to control the flow thereof through the device.

As shown in FIG. 3, the insulating spool 38 and the coil 32 wound thereon are enclosed by the flux path shields 34. This arrangement may be modified, if desired, as illustrated in FIG. 4, by fitting an insulating tube 54 between the solenoid coil 32 and the flux path shields 34 to provide further protection for the coil.

It is apparent that the magnet 48 provides a force in addition to that of the spring 37 to retard the upward movement of the armature 46 in response to the energization of the coil 32. This provides a time delay action so that the switch does not respond immediately to energization of the coil. This time delay action may also be provided by other devices, such as suction cups, as illustrated in FIGS. 5 and 6, by way of example and not limitation. A shaft 56 is secured to the plunger 46' and extends downwardly therefrom in a position to support a disc 58 on its lower end for universal movement. The disc 58 is loosely fitted within a cup 60 which is mounted beneath the coil 32 for rotational adjustment through a thread engagement with a supporting sleeve 61. The bottom of the cup 60 and the bottom of the disc 58 are complementarily shaped, each being provided with a pair of oppositely raised quadrant sectors 64 and 66, respectively, so that changes in their relative angular positions effect changes in the area of surface contact between them. The cup 60 contains oil to a depth to be above the level of the contacting surfaces of the sectors 64 and 66 which are machined to be perfectly flat. The oil wets the contacting surfaces and creates an adhesive force between them to delay the response of the plunger 46' when the solenoid coil is energized and to provide a snap action closing at the end of the delay period.

The time delay may be varied by rotating the cup 60 to adjust the contact area of the sectors and the total adhesive force produced thereby. The disc 58 is universally tiltable on the rod 56 which is fixed to the plunger 46', the plunger containing a slot 68 in which a projection 69 of the shield 34 extends to retain the plunger against rotation. A spring detent finger 71 is mounted on the sleeve 61 for engaging the annular row of corrugations on the cup 60 to hold it in the selected position after adjustment. It will be appreciated, of course, that the time delay device employing the surface tension principle is illustrated only by way of example, and that many other time delay mechanisms including the suction and magnetic devices, may be used to delay the bridging of the contacts 26 for any predetermined time after energization of the coil 32.

A proximity switch 72 according to another embodiment of the invention is illustrated in FIG. 7. The switch includes a solenoid coil 32 which when energized actuates a plunger 73 of magnetizable material to move a nonmagnetic conductive ball 42 into engagement with a pair of contacts 74. The contacts are mounted upon relatively stiff movable conductors 75 of magnetic material which are connected to conductors 30 of a circuit which is to be controlled. The contacts 74 are positioned within the bore of the spool 76 and are biased in a downward direction toward the ball 42 by individual springs 77. The springs are illustrated as being of the compression coil type mounted about the conductors between an insulating cover plate 78 through which the conductors extend and washers 79 or the conductors 75 medially of the lengths thereof.

The exterior portions of the conductors 75 are of substantial width to present a relatively large area to the field of an actuating magnet 81 which is mounted for travel toward and away from the top of the switch. Normally, the conductors 75 rest against the cover plate 78 and support the contacts 74 in a position to be engaged by the ball 42 when it is moved upwardly by the plunger 73 in response to energization of the coil 32. When the magnet 81 approaches the conductors 75, the latter are

attracted and are moved away from the cover plate 78, moving the contacts 74 upwardly out of reach of the ball 42, and thereby opens the circuit through the conductors 30. When the magnet 81 moves away from the device, the biasing springs 77 return the contacts 74 into engagement with the ball 42 if it is in raised position, thus completing the circuit. The circuit is completed across the contacts 74 when the coil 32 is energized and the magnet 81 has not attracted the conductors 75 against the bias of the springs 77. Thus, a circuit can be completed when the coil 32 is energized and the magnet 81 is remote from the switch and can be broken when the magnet 81 overcomes the bias of the springs 77 or when the coil 32 is de-energized.

15 The plunger 73 has the washerlike elements 47 confining the ball 42 and is provided with an enlarged head 82 at its lower end. An angle bracket 83 engages the bottom of the head 82 and limits the downward movement of the plunger 73 and the separation of the ball 42 from the contacts 74.

20 Referring to FIGS. 8, 9 and 10, a further form of the device is illustrated, that wherein housings 84 are made in two similar halves containing coils 85, connected to terminals 86 which extend from opposite faces of the housings. The upper and lower half of the housing contains a U-shaped magnet 87 in its end and a plunger 88 which extends through the center of the coil. The plungers are joined together by a pair of rectangular plates 89 having a pair of apertures 90 therein which loosely confine a pair of balls 91, as clearly illustrated in FIG. 9. The plates 89 are made of insulating material and are provided with aligned studs 92 which are screwed into apertures in the plungers 88. The plungers 88 have enlarged heads 93 which complete the flux path through the adjacent magnet 87 and produce the rapid separation of the balls from the contacts 94 or 95 as the case may be. The contacts are mounted on spring fingers 96 in each half of the housing, the projecting ends 98 forming terminals to which the conductors of a circuit are connected. The housing is split on the center line to permit the assembly of the balls 91, the plungers 88 and the coils 85 therein. The halves of the housing are secured together by screws 80, the housing being secured to a base by bolts in apertures 97. Two single-pole, double-throw switches are contained within the device herein illustrated and such device has been operated for millions of times on five amperes of current without any deleterious effects on the ball surface or the contact faces. The device is not limited to five amperes current and may carry more directly and when the contacts and balls are connected in parallel. When connected in series relation, a plurality of breaks occurs in the circuit, specifically should a separation occur between two points on the ball and the engaged faces of the contacts. In the position illustrated in FIG. 8, in which the upper contacts 94 break a circuit and the lower contacts 95 make a circuit, the energization of the lower coil 85 overcomes the force of the lower magnet 87 to move the plungers 88 upwardly where they are retained by the upper magnet 87 when the coil is deenergized. This movement positively moves the balls 91 from engagement with the contacts 95 and moves them into engagement with the contacts 94. This breaks a circuit across the lower terminals 98 and completes a circuit through the conductors connected to the upper terminals. The energization of the lower coil 85 moves the plungers 88 downwardly and moves the balls from the two sets of contacts 94 to break the circuits therethrough and move the balls into engagement with the sets of contacts 95 to complete circuits thereacross. In this arrangement, the balls are positively moved into and out of engagement with a pair of contacts and are retained in bridging relation to pairs of contacts by the completion of a flux path through one of the magnets 87 and the adjacent plate 93. It is to be understood that a device

25 having a single ball may be employed as a unit and two

such devices are employed to make the device illustrated in FIG. 9, having the two balls. Any number of the units could be stacked to provide a control for a large number of circuits, some of which may be normally closed while others are normally open. It is also to be understood that a single device may be provided having any number of balls therein to form a single unit having a plurality of open and closed contacts.

Referring to FIGS. 11 and 12, a still further form of the invention is illustrated, that wherein a coil 97 has a plunger 98 extending through its center retained therein by the head 99 on one end and a washer 101 threaded or otherwise secured to the other end. The plunger 98 and head 99 are secured to oppositely disposed walls 102 of an inverted U-shaped housing 103. The housing has a back plate 104 secured thereto and provided with a forwardly extending flange 105 at the bottom. A U-shaped element 106 of magnetizable material extends about the coil 97, plunger 98 and head 99, urged downwardly into engagement with the flange 105 by a spring 107. The spring is confined at its ends in aligned apertures in the plunger 98 and the base of the U-shaped element 106.

A plurality of balls 108 are loosely supported in apertures 109 in a pair of insulating plates 111 and 112, the plates being secured by screws 113 to the ends of the U-shaped element 106, as clearly illustrated in FIG. 11. The balls are confined between contacts 94 and 95 which are mounted on spring fingers 96 that extend through the walls 102 with the terminal portions 86 on the outside of the device. When the coil 97 is energized, the U-shaped element 106 is moved upwardly, moving the balls 108 upwardly therewith to break the bridging relation with the contacts 95 and make the bridging relation with the contacts 94. When the coil is de-energized, the element 106 is urged downwardly by the spring 107, moving the ball from engagement with the contacts 94 into engagement with the contacts 95. The balls are rotatively held by the plates 111 and 112 and are positively moved from engagement with one set of contacts into engagement with the other while being capable of rotation relative to the plunger. All four of the circuits through the four balls may be connected in parallel so that the device will have a high current carrying rating, or the circuits may be connected singly, or in pairs for lower current ratings. The balls 108 are freely rotatable within the apertures 109 in the plates 111 and 112 and random indexing will automatically take place so that all points of the balls may engage the contacts to complete the circuits. This prevents repeated arcing at the same point on the ball and protects the surface of the balls and the contacts so that the life of the switch is substantially indefinite. Apertures 114 may be employed to support the bracket in position on a wall or a mounting panel.

The use of a contact ball which is randomly oriented, or indexed during or after every actuation of the switch provides a substantial advantage over fixed contacts as to contact wear and maintenance. The life of the ball is relatively long as compared to the life of a non-indexing type of contact, since in this latter type the make and break points are always the same, and once arcing occurs the contacts deteriorate rapidly. The rotatable ball of the present invention has the make and break points constantly changing in a random manner so that the entire surface of the ball is subjected to relatively even wear. Moreover, the free-floating ball may be readily removed for servicing or replacement since it is not permanently secured in the switch. The switching devices of the present invention may be of the solenoid actuated relay type, or of the proximity type, or of both types, and may be either normally open or normally closed. The conducting coating on the ball permits heavy currents to pass through the device and the positive movement of the ball produces quick separation without arcing or with only a very slight occasional arc.

What is claimed:

1. A magnetically actuatable electrical switch comprising a pair of contacts for connection to an electrical circuit to be controlled, a conductive member for bridging said contacts, means for confining said member for free-floating travel toward and away from said contacts, magnetically actuated means supporting said confining means for moving said member therewith into bridging engagement with said contacts, and means for indexing said member relative to said confining means each time it is moved to present different portions of its surface to said contacts on successive actuations of said switch.
- 15 2. A magnetically actuatable electrical switch comprising a pair of contacts made of an electrically conductive low coercivity magnetic material, an electrically conductive member for bridging engagement with the contacts, magnetically actuated means loosely securing said conductive member and positively moving it into and from engagement with said contacts, and means for indexing 20 said member relative to said confining means each time it is moved to present different portions of its surface to said contacts on successive actuations of said switch.
- 25 3. In a magnetically actuatable electrical switch, a coil, a pair of contacts resiliently mounted adjacent to one end of said coil, a plunger within said coil movable toward said contacts in response to energization of said coil, a ball of conductive material between said contacts and said plunger, means loosely securing said ball to said plunger so as to be positively moved thereby to and from the contacts, and means for indexing said ball relative to said first mentioned means each time it is moved to present 30 different portions of its surface to said contact on successive actuations of said switch.
- 35 4. In a magnetically actuatable electrical switch, a coil, a pair of contacts resiliently mounted adjacent to one end of said coil, a plunger within said coil movable toward said contacts in response to energization of said coil, a ball of conductive material between said contacts and said plunger, means loosely securing said ball to said plunger 40 so as to move therewith into bridging engagement with said contacts, and means for indexing said ball relative to said first mentioned means each time it is moved to present different portions of its surface to said contacts on successive actuations of said switch, said contacts being 45 arranged at an angle to each other to have the ball have a rolling and wiping action with the contacts to assure a full conducting engagement therebetween.
- 50 5. In a magnetically actuatable time delay switch, a pair of electrical contacts for connection to an electrical circuit to be controlled, a conductive member, means for confining said member for free-floating movement relative thereto and for movement therewith toward and away from said contacts, magnetic flux producing means for moving said member into bridging engagement with said 55 contacts, means for indexing said member relative to said confining means each time it is moved to present different portions of its surface to said contacts on successive actuations of said switch, and means delaying the response of said member to said magnetic flux producing means.
- 60 6. In a magnetically actuatable electrical switch, a coil having an aperture, a pair of contacts mounted adjacent to one end of said coil, a plunger movably fitted within said aperture and movable toward said contacts in response to energization of said coil, a ball of conductive material 65 loosely fitted to said plunger for positive movement therewith into engaged and disengaged relation with said contacts, means for indexing said ball relative to said plunger each time it is moved to present different portions of its surface to said contacts on successive actuations of said switch, and time delay means retarding the movement of said plunger upon the energization of said coil.
- 70 7. In a magnetically actuatable switch, a coil having an aperture, a pair of electrically conductive contacts adjacent to said coil, a plunger in said aperture, a ball 75

loosely secured to said plunger and carried therewith, spring means biasing said plunger away from said contacts, and a permanent magnet acting as a stop against which said spring urges the plunger to add a further holding force which resists the movement of the plunger toward the contacts.
